UNITED STATES PATENT OFFICE.

EDWARD R. BALES, OF CENTRALIA, ILLINOIS.

LUBRICATING DEVICE.

Application filed July 23, 1921. Serial No. 486,963.

To all whom it may concern:

Be it known that I, EDWARD R. BALES, a citizen of the United States, and a resident of Centralia, in the county of Marion and 5 State of Illinois, have invented a new and Improved Lubricating Device, of which the following is a full, clear, and exact description.

This invention relates to a device for 10 lubricating the air cylinders of a two-stage air compressor and is primarily designed for use with air compressors used on locomotives.

The object of this invention is to provide 15 a reliable and efficient lubricator for the cylinders of an air compressor that may be fed from some convenient place for filling an oil cup.

A further object is to introduce a lubricator having an oil cup with a restricted feed opening therein which checks the flow of the oil and prevents an over supply of oil by a careless operator.

These objects are accomplished by providing in conjunction with the cylinders of 20 an air compressor a pipe line which extends to a convenient place for feeding the oil and drawing the oil through the pipe line valves and a T on the suction stroke, thus 25 atomizing it.

These and other objects will be more clearly understood from the detailed description and accompanying drawings.

Figure 1 is a plan view showing the lubricator connected to the cylinders of a two-stage air compressor; and

Figure 2 is a vertical section of the lubricator.

Referring to the above-mentioned figures, 40 10 and 11 are the cylinders of a two-stage air compressor. A pipe line 12 is connected to the high pressure cylinder 10. This pipe line 12 extends from the compressor to a convenient place for feeding the oil. For 45 instance, in the case of a compressor used with a locomotive, the pipe line would extend into the cab of the locomotive. Mounted on the upper end of the pipe line is a cup 16 which has a hole 17 drilled in the bottom. 50 The bottom of the oil cup around the drilled hole is beveled so that the oil in passing through the hole 17 will not run along the sides but will drop into the pipe. In the pipe 12 just below its junction with the oil 55 cup 16 perforations 18 are drilled. Located in the pipe line near the high pressure cylinder

are two check valves 13 and 14 and a T 15, which is vertically positioned between the check valves. Connected to the T 15 is a pipe 19 extending for some distance at 60 or nearly at right angles and leading into the low pressure cylinder 11. This T, as will be seen from the description of the operation of the device, acts something like a divider for the oil.

The operation of the device is as follows: 65 Oil is fed into the cup 16 which prevents an excessive amount being fed to the cylinders. The oil passes through the hole 17 and drops into the pipe 12, and on the suc-

tion stroke of the low pressure cylinder 11 it is drawn through the check valve 14 and passes onto the T 15. The heavier particles of the oil will drop through the T 15 while 70 the finer particles will be drawn into pipe 19 with the air which is drawn in through perforations 18 in the pipe line. The oil, which is drawn into pipe 19 in a more or less atomized state, passes into the low pressure cylinder 11.

On the pressure stroke of the piston in the low pressure cylinder 11 air 75 will be forced through pipe 19, pipe 12 and check valve 13, carrying with it the oil that has dropped through T 15. The forcing of the oil through the curved pipe line and the check valve breaks it up into an atomized state 80 and in this state it is conveyed into the high pressure cylinder 10. The check valve 14 prevents the flow of air in the direction of the oil cup during the pressure stroke of the piston in the low pressure cylinder 11, and the check valve 13 prevents the back- 85 ward flow of air during the pressure stroke of the piston in the high pressure cylinder 10.

Claims:

A lubricating system for two-stage air compressor cylinders, comprising an oil cup, a branched pipe line connecting the oil cup with the cylinders, a check valve located 90 between the oil cup and the low pressure cylinder near the latter, a second check valve located between the high pressure cylinder and the low pressure cylinder, the pipe line between said check valves being vertical so 95 that gravity assists in feeding the oil toward the check valve next the high pressure cylinder, and a T in vertical position connecting the pipe line between the valves, said T 100 serving as a divider.

EDWARD R. BALES.
